UNITED STATES PATENT OFFICE.

GRANT JACOBS, OF SAC CITY, IOWA, ASSIGNOR OF ONE-HALF TO GEORGE W. PATEE, OF SAC CITY, IOWA.

GREASE-GUN.

1,175,267.

Specification of Letters Patent. Patented Mar. 14, 1916.

Application filed May 25, 1914, Serial No. 840,907. Renewed November 5, 1915. Serial No. 59,884.

To all whom it may concern:

Be it known that I, GRANT JACOBS, a citizen of the United States, residing at Sac City, in the county of Sac and State of Iowa, have invented a certain new and useful Grease-Gun, of which the following is a specification.

The object of my invention is to provide a grease gun of comparatively simple, durable and inexpensive construction.

More particularly, it is my object to provide a grease gun having a receptacle preferably cylindrical in form for hard oil or grease, especially adapted for transmissions and the like and to provide a sliding airtight partition in said receptacle; and to provide further a pump for forcing air into said receptacle above the partition for thereby forcing the partition downwardly by air pressure for forcing the grease from the receptacle.

Still a further object is to provide a cap for said receptacle having an enlarged annular chamber communicating with said pump.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a side elevation of a grease cup embodying my invention. Fig. 2 shows a central, vertical, transverse, sectional view of the same, and Fig. 3 shows a vertical, transverse view through the air outlet valve.

In the accompanying drawings, I have used the reference numeral 10 to indicate generally a receptacle preferably cylindrical in form having screwed upon its lower end a cap which has a central opening around which is a downwardly extending annular internally screw threaded flange 12. Screwed into the flange 12 is a curved outlet tube 13. Screwed into the outer end of the tube 13 is a discharge nozzle 14.

I preferably provide some means for forming an annular chamber around the upper end of the cylinder 10 of greater diameter than the cylinder 10. My purpose can be so accomplished by using a cap 15 having a downwardly extending annular flange 16 screwed upon the upper end of the cylinder 10 and having just above the flange 16 an

annular chamber 17 of the kind mentioned. Secured at its ends to the sides of the cylinder 10 is a handle 18 which may be of any desired size or shape.

Mounted on the cylinder 10 are two laterally extending brackets 19 formed on which, at their outer ends, are bearings 20 to receive a pump 21. The pump 21 may be of ordinary construction suitable for the purpose, with a screw cap 21^a as shown and is provided with an outlet tube 22, the discharge end of which communicates with the annular chamber 17 as shown in Fig. 2. Communicating with said annular chamber 17 is an outlet valve 23 which may be turned to prevent the exit of air from the interior of the cylinder or may be turned to position to cause said cylinder to communicate with the outer air through the valve. In the tube 22 is an ordinary check valve 24.

Slidably mounted within the interior of the receptacle 10 is a piston preferably comprising two annular leather rings 25 superimposed one upon the other. These rings are the ordinary cup-shaped leathers, the upper one having its periphery turned upward at 26 and the lower one having its periphery turned downward at 27. Above the upper ring 25 is an annular plate 29, and below the lower plate 25 is a similar annular plate 29, each being of smaller diameter than said leather rings. The leathers and the plates 25 are secured together by means of a bolt 30, and a nut thereon.

The pump and cylinder may be assembled by removing the cap 21^a and sliding the pump cylinder upwardly through the bearings 20 until the tube 22 is inserted into the opening provided for it in the lower wall of the annular chamber 17.

In the practical use of my improved grease gun, after the parts have been assembled, the valve 23 is opened and the piston, hereinbefore described, is pushed to the top of the receptacle 10. The valve 23 is then closed and the receptacle is inverted and filled with grease 31. The cap 11 may then be screwed on and the device is ready for use. By operating the piston 32 of the pump by means of the handle 33 on the stem 34, air may be forced through the tube 22 into the annular chamber 17 and therefrom into the upper portion of the receptacle 10. The pressure of the air in said upper portion of the receptacle 10 will force

the piston downwardly, thereby forcing the grease 31 outwardly through the tube 13 and the nozzle 14.

On account of the peculiar construction 5 of the cap 15 and the brackets 19 with relation to the tube 22, the assembling of the pump and the cylinder 10 is quickly and easily accomplished.

The flange 12 is of sufficient length to permit 10 the tube 13 to be rotated for pointing the nozzle 14 in any desired direction for giving it convenient access to gear casings and the like. The annular chamber 17 is of considerable importance insomuch as when 15 the piston is forced to the top of the receptacle 10 the portion 26 of the upper leather 25 may spread out. The head of the bolt 30 will engage the cap 15 and air can then be forced past the portion 26 into the top of 20 the cap 15 for starting the piston downwardly.

It will be understood that some changes may be made in the details of the construction of my improved grease gun without departing from its essential features, and it 25 is my intent to cover by this application any such changes which may be included within the scope of the following claims.

I claim as my invention:

30 1. In a device of the class described, a receptacle having a discharge outlet at one

end, a piston slidably mounted in said receptacle, a cap for said receptacle having an annular downwardly extending flange fitting the upper end of said receptacle and 35 being formed with an annular chamber above said flange of greater diameter than the diameter of said receptacle, a pump, a tube communicating with said pump and with the lower part of said annular chamber. 40

2. In a device of the class described, a receptacle, having an outlet opening and a piston mounted in said receptacle, said receptacle being formed with an annular 45 chamber at its end opposite the discharge outlet of greater diameter than the diameter of said receptacle, a pump having a discharge tube extended through the lower wall of said annular chamber, an adjustable outlet valve communicating with said annular chamber, brackets on said cylinder capable of holding said pump and of permitting longitudinal movement of the pump for assembling the parts with said tube in said wall 50 of said annular chamber.

Des Moines, Iowa, May 18, 1914.

GRANT JACOBS.
